(57) **CLAIM**

The ornamental design for a fabric, as shown and described.

DESCRIPTION

FIG. 1 is a front perspective view of a fabric, showing my new design therefore;

FIG. 2 is a top view thereof;

FIG. 3 is a side view thereof; with all sides being mirror images thereof;

FIG. 4 is a front perspective view of a second alternate embodiment of a fabric;

FIG. 5 is a top view thereof; and,

FIG. 6 is a side view thereof; with all sides being mirror images thereof.

The broken lines in the drawings represent environmental subject matter that forms no part of the claimed design.
